OTHER PUBLICATIONS

US D775,903, 01/2017, Seiders et al. (withdrawn)
(Continued)Primary Examiner — Marianne N Pandozzi
Assistant Examiner — Jae Liang(57) **CLAIM**

The ornamental design for a beverage container, as shown and described.

DESCRIPTION

FIG. 1 is a front, top perspective view of a beverage container showing our new design;

FIG. 2 is a rear, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the beverage container that form no part of the claimed design. The unshaded surfaces bounded by broken lines form no part of the claimed design.
